UNITED STATES PATENT OFFICE.

ANTHONY ROSS AND JAMES McINTOSH, OF MEMPHIS, TENNESSEE.

IMPROVEMENT IN SMOKE-STACKS FOR LOCOMOTIVES.

Specification forming part of Letters Patent No. 152,418, dated June 23, 1874; application filed February 11, 1874.

To all whom it may concern:

Be it known that we, ANTHONY ROSS and JAS. McINTOSH, of the city of Memphis, county of Shelby and State of Tennessee, have invented a Spark-Consuming Smoke-Stack for Locomotive or any other Steam-Boiler, which are heated by wood, coal, or other substances, of which the following is a specification:

The object of our invention is to obviate the throwing of sparks out of the stacks of locomotives and other boilers, by causing the sparks to take a continuous up-and-down movement in the stack until they escape as a fine dust, unable to set anything on fire.

Figure I, in the drawing, represents a vertical section over line *k l*. Fig. II, in the drawing, represents elevation of stack, attached to end of a locomotive-boiler.

a, outside shell of smoke-stack; *b*, inside stack leading from smoke-box toward deflecting-cone *c*; *c*, deflecting-cone, against which the current of sparks strikes and changes their direction, partly up toward the circular netting *d*, partly downward between the inside and outside stack. Part of these sparks, passing downward, ascend again through the annular opening *f* in inside stack and rise toward cone *c*, against *d*, annular netting; *e*, circular opening through which smoke escapes; *f*, annular opening in inside stack, through which the sparks in descending return toward cone *c*; *g*, circular opening and pipes leading from the space *m* between inside and outside stack down into the smoke-

box. The remainder of the sparks in their downward course, after having passed the annular space *f*, pass through those openings into the smoke-box, and are moved upward toward the cone by the draft in stack. By these means the sparks keep moving up and down until they escape as fine dust through the circular opening *e*. *h*, saddle, by means of which smoke-stack is fastened to smoke-box, and which contains the two pipes *g*, through which the sparks descend into the smoke-box; *i*, platform on which the cone *e* is fastened; *j*, smoke-box.

The arrows indicate the action of the sparks. They are first carried up through the main tube *b* against the cone *c*, which deflects them and causes them to be thrown against the inclined walls of the cap *a*, and thence they fall down into the annular space *m*, the lighter particles being taken up by suction through the annular space *f*, while the heavier particles fall down through the tubes *g*, and are thence again carried up through the main tube.

We claim—

In a smoke-stack the deflecting-cone *c*, annular spaces *f* and *m*, and communicating pipes *g*, all arranged and operating substantially as described.

ANTHONY ROSS.
JAMES McINTOSH.
